ADJUSTABLE POTENTIOMETER

Franklin G. Landis, Kenmore, N. Y., assignor, by
mesne assignments, to Sylvania Electric Products Inc., New York, N. Y., a corporation of
Massachusetts

Application April 16, 1949, Serial No. 87,896

14 Claims. (Cl. 323—74)

1
The present invention relates to adjustable potentiometers and, particularly, to those of a type adapted to serve as a voltage divider for alternating potentials.

Adjustable potentiometers heretofore have been constructed with an elongated element exhibiting substantial electrical resistance between its end terminals and an electrically conductive contact which electrically engages the resistive element and is adjustably positioned along the latter by which to derive from the resistive element a proportionate part of the voltage applied across its terminals. The resistive element is conventionally formed either by a multiplicity of turns of resistive wire or by a graphite coating placed upon a dielectric base material.

There are many instances, as in a conventional volume control of a radio receiver, where the potential applied across the terminals of the resistive element of a potentiometer includes both a unidirectional component and alternating components of which it is desired that only the latter be translated to an electrical circuit connected between one terminal of the resistive element and the slider of the potentiometer. In these instances, it has heretofore been necessary to couple the slider of the potentiometer through a series condenser to the electrical circuit in order that only the alternating components of the impressed voltage may be translated.

There are also many instances, of which the detector circuit of a conventional radio receiver furnishes an illustrative example, where it is desirable to include a low-pass resistor-condenser filter network between the voltage source and a potentiometer across which the voltage is impressed in order that only lower-frequency alternating components of voltages may be applied to the potentiometer. It has heretofore been necessary in these instances to construct such filter networks of electrical components separate and apart from the potentiometer.

In many situations of the type last mentioned, the use of circuit components separate and apart from the potentiometer effects an undesirable increase of the cost of the apparatus with which the potentiometer is associated. This is due not only to the additional cost of the circuit components employed but also to the element of labor required to perform the necessary wiring steps. Additionally, many of the potentiometer constructions heretofore proposed often are subject to electrical failure after repeated operations due to the fact that the slider of the potentiometer directly engages and slides over its resistive ele-

ment. There is also the serious disadvantage heretofore experienced where potentiometers are necessarily associated with a number of associated components that the potentiometer and associated

5 components necessarily occupy a volume of space much larger than desirable in many applications. This is particularly true in the field of small so-called personal radios of the portable type and in hearing aids where it is most desirable that the 10 apparatus be enclosed within the most compact carrying case possible.

It is an object of the present invention, therefore, to provide a new and improved adjustable potentiometer which avoids one or more of the 15 limitations and disadvantages of those heretofore proposed.

It is an additional object of the invention to provide an adjustable potentiometer wherein resistive and capacitive circuit components which 20 are desirably associated with the potentiometer are included as a part of its construction.

It is an additional object of the invention to provide a novel adjustable potentiometer having integrally formed in the potentiometer structure 25 a plurality of resistive and capacitive circuit components, and yet one which is of simple, inexpensive and compact construction.

It is yet another object of the invention to provide a new and improved adjustable potentiometer 30 having an operating life which may be almost unlimited.

In accordance with the invention, an adjustable potentiometer comprises a planar resistive element exhibiting substantial electrical resistance between its ends, an electrically conductive member supported in insulated relation to all or at least the major portion of the resistive element and including a portion movable along the element, and a planar member of dielectric material continuously positioned between and effecting physical separation of the element and the aforementioned portion of the member to provide capacitive coupling between the member and that 35 area of the element which at any time lies in opposing relation to the aforementioned portion of the conductive member. In many applications of the invention, the dielectric material may be a titanium-dioxide ceramic material which 40 provides a very substantial capacitive coupling between the movable member and the resistive element. One or more conductive elements may be fixedly positioned in spaced relation along the resistive element but separated therefrom by a 45 dielectric material, such as a titanium-dioxide

ceramic, to provide one or more condensers of fixed capacitance coupled to the resistive element.

For a better understanding of the present invention, together with other and further objects thereof, reference is had to the following description taken in connection with the accompanying drawing, and its scope will be pointed out in the appended claims.

Referring now to the drawing, Figures 1 and 1A illustrate respectively in plan view and in cross-sectional elevational view an adjustable potentiometer embodying the present invention in a particular form: Figure 2 is a circuit diagram representing the electrical circuit arrangement of the Figs. 1 and 1A potentiometer as employed in a portion of a circuit of a radio receiver; Figure 3 is a fragmentary view illustrating a modified form of potentiometer embodying the invention; Figure 4 is a fragmentary view in cross section illustrating an additionally modified form of the invention; and Figure 5 is an elevational view in cross section illustrating yet another form of the invention.

Referring now more particularly to Figs. 1 and 1A of the drawing, there is illustrated an adjustable potentiometer having a strip of material or resistive element 10 exhibiting substantial electrical resistance between its ends. The element 10, which is of open-ring-shaped configuration, may comprise a conventional body of graphite or a conventional resistive element formed by coating a dielectric material with graphite. The element 10 is supported on one surface of a member 11 of dielectric material, which preferably is one having a large dielectric constant such as a titanium-dioxide ceramic, a titanium-dioxide magnesium titanate, a titanium-zirconium dioxide ceramic, or the like. The ends of the element 10 are connected electrically to a pair of terminals 12, 13 as by rivets 14 which extend through apertures in the member 11. The member 11 with its resistive element 10 are secured together with a collar 15 of dielectric material on a hollow shouldered bushing 16 in conventional manner as by spinning over the end of the bushing against a shoulder of the collar 15. One end of the bushing 16 externally threaded to receive a nut 17 which, with a washer 18, maintains the potentiometer in position in an aperture of a panel 19 of an apparatus of which the potentiometer forms a component.

The potentiometer also includes an electrically conductive member or slider 20 supported in insulated relation to at least the major length of the resistive element or strip 10 and including a portion 21 movable along the element 10. In particular, the member 20 is secured by a machine screw 22 and washer 23 to one end of a shaft 24, of insulating material, which is journaled in the bushing 16 and is maintained in position in the latter by a lock ring 25 which engages a groove 26 of the shaft 24. The member 20 is of disc shaped configuration but has an extending resilient arm 27 which terminates in the portion 21 of the slider member. A corrugated washer 28 of spring material is assembled between the member 20 and the collar 15 and is restrained against angular motion relative to the latter by pins 29, it being the purpose of the washer 28 to complete an electrical connection between the member 20 and a terminal 30 of the potentiometer. The member 20 and shaft 24 are locked together for unitary movement by any suitable means, as by the provision of a milled flat 31 on the end of the shaft 24 which co-

operates with an aperture of similar configuration provided in the member 20.

In the potentiometer construction thus far described, the portion 21 of the slider member 20 is constrained to move along the resistive element 10 but is continuously spaced from the latter during such movement by the dielectric member 11, the latter thus serving to provide substantial capacitive coupling between the conductive member 20 and that area of the resistive element 10 which at any time lies in opposing relation to the portion 21 of the conductive slider member 20.

The potentiometer also includes a plurality of conductive tabs 32, 33 and 34 which are fixedly positioned at individual spaced points along the length of the resistive element 10 but are separated from the latter by dielectric material to provide capacitive coupling between each such tab and a corresponding point on the resistive element 10. In particular, the conductive tabs 32 and 33 are cemented or otherwise suitably secured to the dielectric member 11 on the side thereof opposite the resistive element 10, while the tab 34 is secured to a layer of dielectric material 35 which in turn is secured directly upon the surface of the resistive element 10, the assembly of elements 34 and 35 upon the element 10 being conveniently accomplished by a suitable cement or the like.

Figure 2 is a circuit diagram representing a typical application of a potentiometer embodying the Figs. 1 and 1A construction in which the potentiometer is used for conventional volume control in a radio receiver. In this arrangement, the circuit elements shown are identified by reference numerals which serve to identify the corresponding structural elements of the potentiometer. The radio receiver is assumed to be of the super-heterodyne type having an output intermediate-frequency transformer 38 the windings of which are tuned by condensers 39 and 40 to the intermediate frequency. The secondary winding of the transformer is coupled to the anode of a diode rectifier 41 and to the terminal 12 of the potentiometer, the cathode of the rectifier being coupled to the terminal 13 of the potentiometer. The conductive tabs 32 and 33 of the potentiometer are connected to the terminal 12, which is connected to ground as indicated, while the tab 34 of the potentiometer is coupled to ground through a resistor 42 which constitutes with the condenser 34 a conventional tapped-volume-control arrangement. The terminal 30 of the potentiometer is connected to the control electrode of an audio amplifier tube 43 having an input-circuit resistor 44. The portion of the resistive element 10 of the potentiometer lying between the conductive tabs 32 and 33 is indicated in Fig. 2 by the resistor 10a, while the portions of the resistive element between the tabs 33 and 34 and between the tab 34 and the terminal 12 are represented by respective resistors 10b and 10c. The capacitive coupling between the portion 21 of the slider member 20 of the potentiometer and the resistive element 10 is indicated in Fig. 2 by a condenser 21 which, since the slider portion 21 of the potentiometer may be positioned at any point along the resistive element 10 between the terminal 12 and the tab 33, is indicated as adjustably coupled to the portions 10a and 10c of the resistive element by a slidably tap.

It will be apparent from this circuit arrangement that the tabs 32 and 33 in conjunction with that portion of the resistive element 10 lying be-

tween these tabs forms a conventional low-pass filter used to insure that there shall be applied to the portions 10_b and 10_c of the potentiometer only the unidirectional and audio-frequency components of a modulated carrier-wave rectified by the rectifier 41. The tab 34 and resistor 42 form a conventional base compensating network effective for low volume settings of the volume control. The conductive slider member 20 is only capacitively coupled to the portions 10_b and 10_c of the resistive element 10, and consequently only the audio-frequency components of the applied potential are applied from the output terminal 30 of the potentiometer to the audio-frequency amplifier tube 43. It will be apparent from this circuit arrangement that a potentiometer embodying the invention inherently includes in its construction most of the numerous circuit components which are employed in a conventional network used to couple a modulation-signal detector to an audio-frequency amplifier stage. While the resistors 42 and 44 are indicated as circuit components separate and apart from the potentiometer, it will be apparent that the resistor 42 may comprise one formed by printing or painting the resistor in conventional manner on the lower surface of the dielectric member 11 between the conductive tab 34 and the terminal 12 and the resistor 44 may be similarly formed on the upper surface of the member 11. Thus all of the resistive and capacitive circuit components shown in the arrangement of Fig. 2 may readily and easily be incorporated in the potentiometer itself.

Figure 3 illustrates a portion of a potentiometer embodying the invention in a modified form, elements of Fig. 3 corresponding to similar elements of Figs. 1 and 1A being designated by similar reference numerals. In this modification the resistive element 10 is extended beyond the terminal 12 and the terminal 30 is bent down and electrically connected to the end of the resistive element by a rivet 46 which extends through the dielectric member 11. With this construction, the portion of the resistive element 10 between the terminals 12 and 30 may form the fixed resistor 44 shown in the arrangement of Fig. 2. It will be evident, of course, that the portion of the resistive element 10 which lies between the terminals 12 and 30 might alternatively be placed on the upper surface of the element 11, rather than on its lower surface, where this construction more conveniently enables the attainment of different values of resistance for the element 10 and the extended portion thereof.

Figs. 1 and 1A of the drawing indicate that the dielectric member 11, which provides the capacitive coupling between the slider member 20 and the resistive element 10, has substantial thickness. This, however, is done only for purposes of clarity of illustration and it will be understood that in practice the thickness of the member 11 is normally the minimum value that can be tolerated while still providing adequate mechanical strength for the element.

In those applications where it is desired that even larger values of capacitive coupling be provided between the elements 10 and 20, the modified form of the invention illustrated in Figure 4 may be employed. In this arrangement, the dielectric member 11' merely serves as a support for the resistive element 10, and the arm 27 of the conductive slider member 20 terminates in a contact structure 50. The latter is comprised by a plurality of condenser plates 51 75

sandwiched between a plurality of layers 52 of dielectric material with alternate ones of the plates electrically connected to the arm 27 of the conductive slider member and the intervening plates electrically connected to a conductive contact member which effects electrical engagement with the surface of the resistive element 10. The condenser plates 51 may conveniently be formed as U-shaped members as indicated, and the condenser elements 51 and 52 may be assembled as a unitary structure by cementing or otherwise securing the elements together.

Figure 5 illustrates an adjustable potentiometer embodying an additionally modified form of the invention, elements of Figure 5 corresponding to similar elements of Figs. 1 and 1A being indicated by similar reference numerals and analogous elements by similar reference numerals primed. For simplicity, only the major constructional features are shown. A dual potentiometer arrangement is illustrated wherein one potentiometer is comprised by the resistive element 10, the conductive slider member 20 and the shaft 24'. A ring 54 of dielectric material, 25 having a large dielectric constant is positioned on the element 10 to provide the desired capacitive coupling between the latter and the conductive slider member 20'. The second potentiometer comprises a similar ring-shaped resistive element 55, which is positioned on the opposite side of the dielectric supporting member 11', and a conductive slider member 56 mechanically connected to a hollow shaft 57 which surrounds the shaft 24' of the first potentiometer. A ring 58 of dielectric material is likewise used in the second potentiometer to provide the capacitive coupling desired between the resistive element 55 and the slider member 56. The potentiometer structure is maintained in assembled relation by the provision of a collar 59 on the shaft 57, a housing 60 having an annular seat 61 at its open end to receive the dielectric member 11', a set screw 62 which engages a groove 63 in the shaft 24', and a locking ring 64 which is seated in a groove 65 of the shaft 57.

It will be apparent from the several modified forms of the invention disclosed that an adjustable potentiometer embodying the invention is adaptable to numerous types of construction, and that it has utility in a wide range of applications. A potentiometer embodying the invention has the advantages of great compactness, simplicity of construction, and relatively low manufacturing cost. The present invention makes it possible to eliminate many of the circuit components ordinarily employed in an electrical circuit in association with a potentiometer, and this without adding materially to the cost of the potentiometer.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

I claim:

1. An adjustable potentiometer comprising, a strip of material exhibiting substantial electrical resistance between its ends, and an electrically conductive member supported in insulated relation to at least the major length of said strip and including a contact structure electrically engaging said strip and movable therealong, said con-

tact structure comprising a plurality of condenser plates sandwiched between a plurality of layers of dielectric material with alternate ones of said plates electrically connected to said conductive member and the intervening plates electrically connected to a conductive contact member which effects said electrical engagement with said strip, whereby said first-mentioned conductive member is capacitively coupled to that area of said strip which at any time is engaged by said contact structure. 10

2. An adjustable potentiometer comprising, a resistive element exhibiting substantial electrical resistance between its ends, and an electrically conductive member movably supported in insulated relation to at least the major length of said element and including a contact structure mechanically and electrically engaging said element and movable therealong, said contact structure comprising a condenser having one terminal mechanically and electrically connected to said member and a second terminal effecting said mechanical and electrical engagement with said element, whereby said member is capacitively coupled to that area of said element which at any time is engaged by said contact structure. 15

3. An adjustable potentiometer comprising, a strip of material exhibiting substantial electrical resistance between its ends, an electrically conductive member supported in insulated relation to at least the major length of said strip and including a portion movable along said strip and electrically coupled to that area of said strip which at any time lies in opposing relation to said movable portion, and a conductive tab fixedly positioned at a selected point along the length of said strip but separated therefrom by dielectric material to provide capacitive coupling between said tab and said selected point of said strip. 20

4. An adjustable potentiometer comprising, a strip of material exhibiting substantial electrical resistance between its ends, an electrically conductive member supported in insulated relation to at least the major length of said strip and including a portion movable along said strip and electrically coupled to and that area of said strip which at any time lies in opposing relation to said movable portion, and a plurality of conductive tabs fixedly positioned at individual spaced points along the length of said strip but separated from said strip by dielectric material to provide with a portion of said strip a filter network comprised by capacitive and resistive elements. 25

5. An adjustable potentiometer comprising, a planar member of relatively rigid thin titanium-compound dielectric sheet material, a resistive material of open-ring-shaped configuration supported by and in engagement with one surface of said member and exhibiting substantial electrical resistance between its ends, and a pivoted electrically conductive member supported in insulated relation to at least the major length of said resistive material and including a portion engaging the opposite surface of said dielectric member and movable in an arc along said resistive material in opposing relation thereto, said dielectric member providing substantial capacitive coupling between said conductive member and that area of said resistive material which at any time lies in opposing relation to said portion of said conductive member. 30

6. An adjustable potentiometer comprising, a planar open-ring-shaped member of relatively rigid thin titanium-compound dielectric sheet 35

material, a resistive material of open-ring-shaped configuration integrally formed with said member on one surface thereof and exhibiting substantial electrical resistance between its ends, and a pivoted electrically conductive member supported in insulated relation to at least the major length of said resistive material and including a portion engaging the opposite surface of said dielectric member and movable in an arc along said resistive material in opposing relation thereto, said dielectric member providing substantial capacitive coupling between said conductive member and that area of said resistive material which at any time lies in opposing relation to said portion of said conductive member. 40

7. An adjustable potentiometer comprising, an electrically continuous resistive element exhibiting substantial electrical resistance between its ends, an electrical terminal at each end of said element, a conductive tab affixed with intervening dielectric material in opposing relation to an intermediate fixed point on said element spaced from one terminal thereof, and an electrically conductive member supported in insulated relation to at least the major length of said element and including a portion movable along said element between said one terminal thereof and said intermediate fixed point and capacitively coupled to said element. 45

8. An adjustable potentiometer comprising, an electrically continuous resistive element exhibiting substantial electrical resistance between its ends, an electrical terminal at each end of said element, a conductive tab affixed to said element at a fixed point intermediate the ends thereof but spaced from said element by dielectric material and electrically connected to one of said terminals, and an electrically conductive member supported in insulated relation to at least the major length of said element and including a portion movable along said element between said one terminal thereof and said intermediate fixed point and capacitively coupled to said element. 50

9. An adjustable potentiometer comprising, an electrically continuous resistive element exhibiting substantial electrical resistance between its ends, an electrical terminal at each end of said element, a plurality of conductive tabs affixed to said element at individual fixed spaced points intermediate the ends thereof but with each tab spaced from said element by dielectric material and electrically connected to one of said terminals, and an electrically conductive member supported in insulated relation to at least the major length of said element and including a portion movable along said element between said one terminal thereof and one of said intermediate fixed points and capacitively coupled to said element. 55

10. An adjustable potentiometer comprising, an open-ring-shaped electrically continuous resistive element exhibiting substantial electrical resistance between its ends, an electrical terminal at each end of said element, an electrical terminal intermediate said last mentioned terminals, resistive material between one of said first mentioned terminals and said intermediate terminal, and a pivoted electrically conductive member electrically connected to said intermediate terminal and including a portion movable in an arc along said resistive element in capacitively coupled relation thereto. 60

11. An adjustable potentiometer comprising, an electrically continuous resistive element exhibiting substantial electrical resistance between 65

its ends and including an end portion which has a different value of resistance per unit length than does the remainder of said element, electrical terminals at each end of said element and at each end of said portion thereof, and an electrically conductive member electrically connected to the remote terminal of said end portion and including a portion movable along said element and capacitively coupled thereto.

12. An adjustable potentiometer comprising, an electrically continuous resistive element exhibiting substantial electrical resistance between its ends, electrical terminals at each end of said element, a terminal intermediate said last mentioned terminals, resistive material between one of said first mentioned terminals and said intermediate terminal, a conductive tab affixed to said element at a fixed point intermediate the ends thereof but spaced from said element by dielectric material, and an electrically conductive member electrically connected to said intermediate terminal and including a portion movable along said element between said one terminal thereof and said intermediate fixed point and capacitively coupled to said element.

13. An adjustable potentiometer comprising, an electrically continuous resistive element exhibiting substantial electrical resistance between its ends, electrical terminals at each end of said element, a terminal intermediate said last mentioned terminals, resistive material between one of said first mentioned terminals and said intermediate terminal, a plurality of conductive tabs affixed to said element at individual fixed spaced points intermediate the ends thereof but each spaced from said element by dielectric material and electrically connected to said one terminal, and an electrically conductive member electri-

cally connected to said intermediate terminal and including a portion movable along said element and capacitively coupled thereto.

14. An adjustable potentiometer comprising, a planar member of relative rigid thin sheet dielectric material having a large dielectric constant, resistive material of open-ring shaped configuration supported in engagement with one planar surface of said member and exhibiting substantial electrical resistance between its ends, and a pivoted electrically conductive member supported in insulated relation to at least the major length of said resistive material and including a portion engaging the opposite planar surface of said dielectric member and movable in an arc along said resistive material in opposing relation thereto, said dielectric member providing substantial capacitive coupling between said conductive member and that area of said resistive material which at any time lies in opposing relation to said portion of said conductive member.
